UNITED STATES PATENT OFFICE.

THEODORE BENDER, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A HANDLE OF BUTTON-HOOKS OR SIMILAR ARTICLES.

43,031.

Specification for Design.

Patented Sept. 24, 1912.

Application filed June 24, 1912. Serial No. 705,668. Term of patent 7 years.

To all whom it may concern:

Be it known that I, THEODORE BENDER, a citizen of the United States, residing at Providence, in the county of Providence and State of Rhode Island, have invented a new, original, and ornamental Design for the Handle of a Button-Hook or Similar Article, reference being had to the accompanying drawings.

Figure 1 is a side view of the handle,

showing my design. Fig. 2 is an edge view of the same.

I claim—

The ornamental design for a handle of a button hook or similar article, as shown.

THEODORE BENDER.

Witnesses:

ADA E. HAGERTY,
J. A. MILLER.
